(57) **CLAIM**

The ornamental design for a construction bucket having a sloped interior bottom surface, as shown and described.

DESCRIPTION

1. Construction bucket having a sloped interior bottom surface

FIG. 1.1 is a top perspective view of a construction bucket having a sloped interior bottom surface in accordance with my invention;

FIG. 1.2 is a bottom perspective view of the construction bucket having a sloped interior bottom surface;

FIG. 1.3 is a front view of the construction bucket having a sloped interior bottom surface;

FIG. 1.4 is a side view of the construction bucket having a sloped interior bottom surface;

FIG. 1.5 is a top view of the construction bucket having a sloped interior bottom surface;

FIG. 1.6 is a bottom view of the construction bucket having a sloped interior bottom surface; and

FIG. 1.7 is a cross-sectional view of the construction bucket having a sloped interior bottom surface taken vertically along the line, "7" of FIG. 1.6.

The evenly dashed broken lines depict portions of the construction bucket and environmental subject matter that forms no part of the claimed design. The short dash-short dash-long dash broken lines on the construction bucket depict boundaries to the claim that form no part of the claimed design. The broken lines form no part of the claimed design.
